UNITED STATES PATENT OFFICE.

EDWIN C. PALMER, OF CLEVELAND, OHIO, ASSIGNOR TO THE STANDARD TOOL COMPANY, OF SAME PLACE.

DESIGN FOR A BICYCLE T SADDLE-POST.

SPECIFICATION forming part of Design No. 28,582, dated May 10, 1898.

Application filed September 18, 1897. Serial No. 652,197. Term of patent 3½ years.

To all whom it may concern:

Be it known that I, EDWIN C. PALMER, a citizen of the United States, and a resident of Cleveland, county of Cuyahoga, and State of Ohio, have invented and produced a new and original Design for Bicycle T Saddle-Posts, of which the following is a specification, reference being had to the accompanying drawings, forming a part thereof, and which represent a view of a bicycle T saddle-post embodying my design.

Figure I represents a side elevation of my improved design, and Fig. II represents a left-hand view thereof.

The leading feature of my design consists in an elbow or joint A between an upright member a and a horizontal member a' of markedly smaller diameter than that of member a , forming a T-joint of continuous and

integral structure. The upper end of member a has a hemispherical or an approximately hemispherical configuration, whose upper surface joins the surface of member a' at about the middle of the latter. The said upper surface of member a falls outwardly and downwardly away from the said middle surface of member a' , as shown in Fig. II, and joins the lateral surface of said member a .

What I claim is—

The design for a bicycle T saddle-post, as herein shown and described.

Signed by me this 16th day of September, 1897.

EDWIN C. PALMER.

Attest:

D. T. DAVIES,
A. E. MERKEL.
